UNITED STATES PATENT OFFICE.

GEORGE H. BARTLETT, OF SHORT HILLS, NEW JERSEY.

TOOL-HOLDING BOX.

SPECIFICATION forming part of Letters Patent No. 400,287, dated March 26, 1889.

Application filed October 29, 1888. Serial No. 289,491. (No model.)

To all whom it may concern:

Be it known that I, GEORGE H. BARTLETT, of Short Hills, in the county of Essex and State of New Jersey, have invented certain new and useful Improvements in Tool-Holding Boxes; and I do hereby declare that the following is a full, clear, and exact description thereof, reference being had to the accompanying drawings, and to the letters of reference marked thereon, which form a part of this specification.

This invention relates to an improved box, tool holder or receptacle of that kind having a series of separate compartments or cells, each of which is adapted to receive a single article—such as is commonly used for auger-bits or similar tools.

A box embodying my invention is made of wood or similar substances, and is provided with a series of elongated cells formed in a block side by side and parallel with each other, with their open ends at one side or face of the block. Said block consists of three or more pieces or slabs of wood, the exterior pieces or slabs having recesses formed in their inner faces, and the intermediate pieces having recesses in both faces, which recesses, when the pieces or slabs are secured together, form the several compartments of the tool-holder.

30 A recessed cover is connected with the top of the block thus made to hold the tools in place.

In the accompanying drawings, Figure 1 is a perspective view of a tool holder or receptacle constructed in accordance with my invention. Fig. 2 is a transverse section thereof. Fig. 3 is an end view showing the connection between the cover and box, and showing the cover lifted away from the box. Fig. 4 is an end view of a box differing somewhat from that shown in Figs. 1, 2, and 3. Fig. 5 is a front elevation of the top of the box shown in Fig. 4. Fig. 6 is a box-cover differing slightly from the one shown in Fig. 1. Fig. 7 shows a cover hinged to the body of the box.

45 As shown in Figs. 1, 2, and 3, A is the main part or body of the receptacle, and B the cover thereof. The main part or body consists of a single block, which is formed by three separate layers or slabs, A' A² A³, secured together side by side by means of glue or otherwise. The slabs A' A³, forming the front and

rear surfaces of the block, are provided at their inner faces with recesses a' a' a³ a³. The intermediate slab, A², is provided at one side with recesses a² a², and at its opposite side with recesses a⁴ a⁴. The recesses a' a² form one set or row of cells or compartments, while the recesses a³ a⁴ form another set or row of cells or compartments when the several layers are secured together. The grooves or recesses a' a² a³ a⁴ do not extend throughout the entire length of the slabs or layers, but are terminated short of the bottom ends of the layers, so that when the layers are placed and secured together the wood left at the ends of the recesses forms the bottom of the cells. By the employment of this construction no special means for closing the cells at their lower ends is required, and the labor and expense of applying a separate piece or pieces for this purpose are avoided.

It will of course be understood that in constructing the box the grooves may be formed in the slabs by running the same over revolving cutters, in a manner heretofore common and well known. In constructing the tool-holder, therefore, the slabs or layers A' A² A³ will first be cut the proper length, and the recesses a' a² a³ a⁴ will be formed therein by the employment of a revolving cutting-tool, in the manner above stated. The slabs will then be secured together to form a block, in the manner above described.

The cover B consists of a piece of wood, which is provided on its under or inner surface with grooves or recesses b b', each of which extends over a row of cells or compartments in the block A, said grooves or recesses therefor being located at right angles to the central lines of the cells and parallel with the sides of the slabs forming the block.

In constructing a cover provided with recesses of the character described a long strip or board will first be grooved longitudinally with grooves the proper size and shape to form the recesses b b', and the said board or strip will then be cut into pieces, each of which is of length to form a cover. As shown in Fig. 1, the ends of the grooves b b' of the cover are left open, this construction not usually being of special disadvantage in tool-boxes. If desired, however, for appearance

or to protect the tools from access of air or dampness, filling-pieces $b^2 b^2$ may be inserted and secured in the ends of the grooves, as shown in Fig. 6. In Fig. 5, wherein a cover 5 is shown which is made in a similar manner, end pieces, $b^3 b^3$, are shown as secured to the ends of the cover for closing the ends of said grooves, this construction being especially desirable in the form of cover shown in that figure, for the reason that the grooves of the cover are made exceptionally deep to receive the ends of the tools having long shanks or tangs, and the presence of such deep grooves makes it desirable that the parts of the wood 5 between the grooves should be braced or supported to prevent the cover becoming too easily broken.

A cover embracing the features of construction above described may be connected o with the body of the receptacle or block A by hinges ($a a$, as shown in Fig. 7) or in any other suitable manner.

I have herein shown a novel means of connecting a cover with a box-body having advantages in point of simplicity and economy of construction. As shown in Figs. 1 and 3, C is a cylindric metal rod or piece of stiff wire secured in the cover B, and adapted to engage and slide vertically in a vertical recess, c , formed in the block A. The said rod is adapted to slide freely endwise and to rotate in the recess c , so that by drawing the cover upwardly to free it from the ends of the tools in the block, and by then swinging the cover around by the turning of the rod in said recess, the ends of the tools will be exposed, and the said tools may be easily taken from the cells. C' is a short pin desirably secured in the under surface of the cover, adapted to engage an opposite hole, c' , in the block A, so as to hold the cover from turning when the said cover is in contact with the top of the block. A hook, D, on the block, adapted to engage a stud or projection, d , on the cover, may be conveniently used for holding the cover in contact with the block in handling or transporting the receptacle. The recess c may be conveniently formed in the block A by means of two opposite semicircular grooves, $c^2 c^3$, formed in the adjacent faces of the layers or slabs $A^2 A^3$, said grooves $c^2 c^3$ being formed by the use of a suitable cutting-tool at the same time that the recesses $a' a^3$, constituting the cells, are formed in the said slabs. The recess c' for the pin C' may be formed between the layers or slabs in a similar manner.

In Fig. 4 I have shown a connection between the cover and block A, embracing a rod, E, attached to the cover, which rod is held in eyes or staples $e e$, attached to the side of the block, in which eyes or staples the rod is adapted to slide and turn to permit the removal of the cover from the block. The said rod E is shown as attached to the cover B by having its end bent at right angles and driven into the cover, a staple, e' , serving to hold the

rod perpendicular to the cover. The rod may, however, be otherwise attached to the said cover.

The box shown in Figs. 4 and 5 is also provided with a short pin, E', adapted to engage a staple, e^2 , on one of the sides of the block, for the purpose of holding the cover from moving on the block when the box is closed, in 75 the same manner as before described. The box shown in Fig. 4 is also provided with a hook, D, and stud d , for the purpose above stated.

It will of course be understood that as far 80 as the connection between the cover and block, consisting of a rod attached to the cover and having sliding engagement with a recess in the block, is concerned, the block and cover may be made in the particular 85 manner above described or otherwise—as, for instance, the block A may be made of one piece, as shown in Figs. 4 and 5. It is entirely obvious, furthermore, that the employment of the short pin C' or E' is not es- 90 sential as far as the operation of the cylindric rod attached to the cover and engaging a recess within the block is concerned, inasmuch as the hook D or other fastening device may be relied upon to hold the cover from 95 shifting or turning on the block. Such pin employed in connection with a rod having both sliding and rotating engagement with the receptacle is, however, of especial advantage as affording a secure and convenient 100 means of connecting the parts, and is of especial utility in preventing the cover from being shifted from its place until lifted clear of the tools in the receptacle, and is therefore herein claimed as part of my invention. 105

A tool-holding box made generally in the manner above set forth may be provided with more than two rows of cells or compartments, and in case it has more than two rows of cells will have two or more internal 110 layers instead of a single intermediate layer, such as is shown in the drawings. The cells or compartments for the bits or tools may be of any cross-sectional shape necessary or desirable, according to the purpose for which 115 the holder is to be used.

It has been proposed heretofore to make a tool-receptacle by boring a series of holes side by side in a block of wood to form a series of separate cells. A construction of 120 this kind is not, however, adapted for general use, especially in boxes for long tools, for the reason that the boring of a series of holes side by side is a slow and expensive operation, inasmuch as the holes can seldom 125 be bored straight and parallel with each other, owing to the liability of lateral deflection of the boring-tool by inequalities in the grain of the wood. By making the block of separate layers or slabs grooved partially through 130 their length I construct the block in a simple, cheap, and expeditious manner, while the cover being provided with grooves in the manner described, said grooves being arranged oppo-

site the row of cells, makes a construction in the cover of superior character and great economy.

I claim as my invention—

- 5 1. As a novel article, a tool holder or receptacle consisting of two exterior slabs or layers provided with grooves upon their inner faces which terminate short of the lower ends of the said slabs or layers, and one or more intermediate layers provided with similar grooves upon both faces, said layers being secured together with the grooves therein opposite each other to form a series of compartments or cells, and a cover connected with the 15 upper end thereof, said cover being recessed in its inner face to receive the ends of the tools which project from the compartments or cells, substantially as described.
2. As a novel article, a tool holder or receptacle consisting of two exterior slabs or layers grooved upon their inner faces, and one or more intermediate layers grooved upon both faces, said layers being secured together with the grooves therein opposite each other 25 to form a series of straight rows of compartments or cells, and a cover provided on its inner face with a plurality of grooves arranged severally over the rows of compartments or cells, and forming recesses to receive 30 the ends of the tools which project from said compartments or cells, substantially as described.

3. A tool holder or receptacle consisting of a wooden block provided with a plurality of cells or compartments, combined with a recessed cover and a cylindric rod attached to the cover and fitting and sliding within a guide-recess formed in the said block, substantially as described. 35

4. A tool holder or receptacle provided with a plurality of compartments or cells, combined with a recessed cover, a cylindric rod rigidly attached to the cover and having sliding and rotating connection with the receptacle, and a second shorter rod secured in said cover and 45 having sliding connection with the receptacle, substantially as described. 40

5. A tool holder or receptacle comprising a plurality of slabs or layers grooved on their adjacent faces to form a series of cells or compartments to receive the tools, a cover, and a cylindric rod rigidly attached to the cover, said slabs or layers being provided also with grooves upon their adjacent faces, which form a guide-recess to receive said rod, substantially as described. 50 55

In testimony that I claim the foregoing as my invention I affix my signature in presence of two witnesses.
